RUSSELL G. THOMPSON AND CHESTER W. CRUMRINE, OF ROCHESTER, NEW YORK, ASSIGNEES, BY MESNE ASSIGNMENTS, TO NORTH EAST APPLIANCES, INC., OF ROCHESTER, NEW YORK, A CORPORATION OF NEW YORK.

POWER MECHANISM.

Application filed March 30, 1927. Serial No. 179,629.

This invention relates to power-mechanism for actuating the drive shaft of a calculating machine. It is customary to use an electric motor for this purpose, connected with the drive shaft through gearing which is adapted to reduce the rotative speed and change the direction of rotation as required.

The object of the invention is to combine the motor, the gearing, and a part of the controlling means in a single assembly, with the gearing enclosed in a housing, this assembly being attached to and removable from a standard calculating machine as a self-contained unit and having simple and convenient provision for cooperative engagement with the associated parts of the machine.

To the foregoing end the invention consists in the mechanism hereinafter described, as it is defined in the annexed claim.

In the accompanying drawings, Fig. 1 is a plan view of power mechanism embodying the present invention. Fig. 2 is a partial view of the mechanism, on a larger scale, shown in section approximately on the line 2-2 in Fig. 4. Fig. 3 is a detail view showing particularly the control members of the gearing, and Fig. 4 is an elevation of the power mechanism, looking from right to left in Fig. 1.

The invention is illustrated as applied to a calculating machine of a well-known type, and specifically to the machine known as the Monroe calculating machine. In such a machine there is a casing 5 which encloses a frame having side members 6, of which one is shown in Fig. 1. Journalled on the frame members, near the rear of the casing, is a horizontal drive shaft 7, which may be rotated either manually or by power. This drive shaft carries a series of actuators 8 which cooperate with a series of registering mechanisms 9, in a manner which is well known and need not be described herein.

In the operation of the machine the drive shaft 7 must be rotated sometimes in one direction and sometimes in the other, at a moderate speed, and where an electric motor is used for this purpose it is customary to interpose between the drive shaft and the motor an epicycloidal gearing having provision both for reducing the rotative speed between the drive shaft and the armature shaft of the motor, and for reversing the

direction of rotation of the drive shaft while the armature shaft rotates continuously in the same direction. The present invention does not relate to the construction and mode of operation of the gearing as such, but is directed to simple, compact and convenient means for enclosing and supporting the gearing and the motor, for applying them detachably as a unit to the frame of the calculating machine, and for interconnecting the controlling means of the gearing with the appropriate member of the calculating machine.

The electric motor 10, which is preferably of the enclosed type, is connected rigidly, and preferably integrally, with a gear housing 11, and the end of this housing is closed by a removable end plate 12 secured in place by screws 13. The end plate is provided with perforated lugs 14, that receive screws by which the entire assembly, including motor, housing and end plate, is secured detachably to the frame member 6 of the machine. The gearing 15 is enclosed within the housing, and thus constitutes part of a readily detachable and self-contained assembly with the motor. The housing also provides effective means for enclosing lubricant for the gearing.

The armature shaft of the motor is connected with one end of the gear train, while a short driven shaft 17, in axial alignment with the armature shaft, is connected with the other end of the gear train and journalled in the end plate 12. The power mechanism is mounted upon the frame of the machine with the driven shaft 17 in axial alignment with the drive shaft 7, and these two shafts are interconnected by a simple coupling 18, of which the members may be disengaged by merely withdrawing one from the other when the power mechanism is removed from the machine.

The details of construction of the gear train are not described herein, as it may be of any ordinary or well-known form, but, as is customary in such gearing, the direction of rotation is controlled by arresting alternatively two rotative members, such as the members 19 and 20 shown particularly in Fig. 3. Each of these members is provided with radial arms or detents that cooperate, respectively, with suitable stop members which are thrown alternatively into opera-

tion according to the direction of rotation which is required. For this purpose the calculating machine is customarily provided with a manually operable lever 21, pivoted at 22 upon the frame 6.

In order to interconnect the lever 21 with the gearing enclosed within the removable housing 11, the housing is provided with an offset portion 23 in which a short rock-shaft 10 24 is journalled. This rock-shaft carries arms 25 and 26, and upon these arms spring-controlled stop lugs 27 and 28 are slidingly supported, these lugs being adapted to cooperate with the stop members 19 and 20, respectively. The stop lugs are thrown alternatively into operative position by rocking the shaft 24 in one direction or the other.

One end of the rock-shaft projects through the housing and is provided with a slotted 20 arm 29. A pin 30, projecting from the lever 21, engages the slot in the arm 29, so that by manipulation of the lever 21, in the usual manner, the parts just described may be actuated to cause reversal in the direction of 25 rotation of the drive shaft 7.

It will be apparent that upon removing the screws which fasten the end plate to the frame 6, the entire power mechanism may be

removed as a unit without disengaging any other fastening means, since the coupling 18 30 and the described connections between the lever 21 and the rock-shaft 24 may be separated by the mere operation of withdrawing the power mechanism. The parts may be restored to operating position with equal facility.

The invention claimed is:

The combination, with a calculating machine comprising a frame and a drive-shaft journalled thereon, of reducing and reversing gearing having a driven shaft, a housing enclosing the gearing, a motor rigidly attached to and supported by said housing and with its shaft connected with the gearing to drive the same, means securing said housing 45 removably to the frame of the machine, with the driven shaft in alignment with the drive-shaft of the machine, coupling means connecting said shafts, a gear-controlling member movable within the housing, and means, 50 for moving said member, extending to the outside of the housing and cooperable with a control-member of the calculating machine.
